UNITED STATES PATENT OFFICE

MELZAR H. MOSMAN, OF CHICOPEE, MASSACHUSETTS.

DESIGN FOR A LAMP-STAND.

Specification forming part of Design No. **6,616**, dated April 29, 1873; application filed February 26, 1873.

To all whom it may concern:

Be it known that I, MELZAR H. MOSMAN, of Chicopee, in the county of Hampden and State of Massachusetts, have invented or produced a new and original Design for a Lamp-Stand, the nature of which will be understood from the following description and accompanying photographic illustration.

The letter *a* indicates a foot or base, on which is the figure of a boy, *b*, kneeling and grasping his hat with one hand. To the top of the hat is attached the socket *c*, in which rests the body of the lamp *d*. The other hand of the boy is at his side. By the side of the boy is a "box-trap," indicating that he is a "trapper-boy;" but this box is not essential to the com-

pleteness of the figure. The shape of the foot *a* and of the body *d* may be changed at discretion, as they are not essential features of the design. The essential feature of the design is the figure of the kneeling boy, with one hand grasping his hat; and

I claim as my invention or production—

The design for a lamp-stand, consisting of the figure of a kneeling boy with one hand grasping his hat, the whole having an appearance, substantially as set forth.

MELZAR H. MOSMAN.
